(57) **CLAIM**

The ornamental design for a carrier handle for a can, as shown and described.

DESCRIPTION

FIG. 1 is a side perspective view of the carrier handle showing environmental structure of a carried can in dotted outline being carried in a first position. The perspective view from the other side is a mirror image.

FIG. 2 is another side perspective view of the carrier handle showing environmental structure of a carried can in dotted outline being carried in a second position. The perspective view from the other side is a mirror image.

FIG. 3 is another side perspective view of the carrier handle showing environmental structure of a carried can in dotted outline being carried in a third position. The perspective view from the other side is a mirror image.

FIG. 4 is a side view of the carrier handle. The view from the other side is a mirror image.

FIG. 5 is a front view of the carrier handle taken along the line 5—5 shown in FIG. 4.

FIG. 6 is a bottom view of the carrier handle taken along the line 6—6 shown in FIG. 4.

FIG. 7 is a top view of the carrier handle taken along the line 7—7 shown in FIG. 4, with environmental structure of a carried can being shown in dotted outline; and,

FIG. 8 is a rear view of the carrier handle taken along the line 8—8 shown in FIG. 4.
